(57) **CLAIM**

The ornamental design for a lid with multiple sauce packet recesses, as shown and described.

DESCRIPTION

FIG. 1 is a top perspective view of the lid with multiple sauce packet recesses, according to the present design; FIG. 2 is a front side view of the lid with multiple sauce packet recesses, according to the present design; FIG. 3 is a back side view of the lid with multiple sauce packet recesses, according to the present design; FIG. 4 is a right side view of the lid with multiple sauce packet recesses, according to the present design; FIG. 5 is a left side view of the lid with multiple sauce packet recesses, according to the present design; FIG. 6 is a top side view of the lid with multiple sauce packet recesses, according to the present design; and,

(Continued)

FIG. 7 is a bottom side view of the lid with multiple sauce packet recesses, according to the present design. The circular broken lines define the boundaries of the claim and along with the spaces contained within them, form no part thereof. All other broken lines depict portions of the lid with multiple sauce packet recesses that form no part of the claimed design.

1 Claim, 5 Drawing Sheets
